UNITED STATES PATENT OFFICE.

ALFRED GARTNER, OF WASHINGTON, DISTRICT OF COLUMBIA.

DISPLAY DEVICE.

1,301,117.

Specification of Letters Patent. Patented Apr. 22, 1919.

Application filed January 14, 1918. Serial No. 211,889.

To all whom it may concern:

Be it known that I, ALFRED GARTNER, a citizen of the United States, and resident of Washington, District of Columbia, have invented certain new and useful Improvements 5 in Display Devices, of which the following is a specification.

This invention relates to improvements in display devices, and its object is to provide 10 such a device, of simple and cheap construction, "sensational" and effective when being used.

The invention consists in the improved display device, combining means having an 15 exposed "question" and movable means constituting "concealed" answer, together with illustrations, mottos, words, etc., appropriate to the question or answer, or both, as will be hereinafter more fully described and 20 finally embodied in the clauses of the claim.

In the accompanying drawings:

Figure is a front elevation of my improved display device, showing the essential parts fully exposed to view, and

25 Fig. 2 a top plan view of Fig. 1.

In said drawings, *a* represents a frame or plate, made of wood, metal or other suitable material, in any shape desired, but preferably in the shape of a cartridge, provided 30 with suitable means, such as eyelets *b*, *b* for suspending said frame, and also provided at its rear with brackets *f*, *g* forming bearings for the axle or spindle *d*, which is held in normal position by a spiral spring *e*, 35 all of which is of well known construction.

On the axle or spindle *d* is secured one end of a screen or curtain *c* of thin metal, silk, or other suitable material, the other end of said screen *c* being provided with a 40 bar or pin *o*, to which is secured a cord *p*, by means of which the screen or curtain can be pulled out to view, when desired.

On the frame or plate *a* is printed or otherwise arranged an appropriate question, 45 such as "What will kill kaiserism?", while the screen or curtain *c* is preferably divided up, and contains, besides the appropriate concealed answer, such as an American flag, or another suitable motto or emblem,—illustrations or sentences of patriotic nature, or

otherwise, which displays are intended to connect with or be appropriate to the question and answer.

In the combination illustrated, the American flag constitutes the concealed answer, 55 and the same is supported by the U. S. fighting forces (only one soldier being shown) marching "On to Berlin", and the latter being supported by money partly raised from the sale of "War savings 60 stamps", which fact is brought out by the additional display on the lower end of the screen or curtain.

Preferably the device is suspended with the screen or curtain rolled up or concealed 65 behind the frame or plate, and when "operated" after reading the exposed question, the concealed answer, the American flag, is exposed to view, simultaneously explaining to the operator or inquirer that the army will 70 support the flag, and that money is required to support the army.

It will be manifest that other exposed questions and concealed answers connected with suitable illustrations, words mottos, etc., 75 can be used, and that sliding or disappearing means, of well known construction, can be substituted for the rolling-up means, without changing the scope of my invention.

What I claim as new and desire to secure 80 by Letters Patent is:

1. In a device of the character described, means provided with an inscription constituting a question, and means normally concealed provided with an appropriate answer 85 and with additional display means related to or connected with said answer, said concealed means being adapted to be withdrawn from the first mentioned means and exposed to view to present the answer together with 90 the additional display means.

2. In a device of the character described, means provided with an inscription constituting a question, means normally concealed provided with an American flag as an appropriate answer to the question, and additional display means related to and connected with said American flag, said concealed means and additional display means being adapted 95 to be withdrawn from the first mentioned 100

means and exposed to view to present the American flag and the additional display means.

3. In a device of the character described, means provided with an inscription constituting a question, said means being appropriately shaped to constitute an answer

to the question, means normally concealed adapted to be displayed to present an additional answer, and display means related to and connected with the normally concealed means and adapted to be exposed to view together with the latter.

ALFRED GARTNER.
